Atlys.

UNITED STATES PATENT OFFICE.

GEORGE L. PIERCE, OF BROOKLYN, NEW YORK, ASSIGNOR TO A. G. SPALDING & BROS., OF NEW YORK, N. Y., A CORPORATION OF NEW JERSEY.

CADDY BAG.

Application filed October 26, 1923. Serial No. 671,017.

To all whom it may concern:

Be it known that I, GEORGE L. PIERCE, a citizen of the United States, and resident of Brooklyn, in the county of Kings and State of New York, have invented certain new and useful Improvements in Caddy Bags, of which the following is a specification.

My present invention has to do with caddy bags, and more particularly with a pocket therein which may be made to receive golf balls, golf shoes, or other articles.

The principal object of my invention is the provision of a pocket on the bag so located and constructed that when articles are placed therein, the same is not evident from the exterior appearance of the bag.

Another and important object of my invention is the provision of means as above which may be readily incorporated in a caddy bag without material expense, or manufacturing difficulties, and may include means for covering the pockets, which may be done in various manners.

I have illustrated in the drawings, several forms which are to be taken as illustrative of divers ways of carrying out my invention.

In these drawings:—

Figure 1 is a front view of the complete bag.

Fig. 2 is a vertical section through a portion of the bag.

Fig. 3 is a fragmentary front view of a modified bag.

Fig. 4 is a vertical section through a portion of the bag of Fig. 3.

Fig. 5 is a similar view with the flaps open.

Fig. 6 is a transverse section of a portion of the bag on line 6—6 of Fig. 4.

Fig. 7 is a detail, showing a modified arrangement of flaps.

The caddy bag of leather, or other suitable material, is shown at 1, which may be of any desired construction, and is provided with an aperture 2 of a shape which will be best determined by circumstances. In one instance it may be found best to form the pocket as by means of applying a pocket lining 3 within the bag 1, sewed to that part of the bag adjacent the aperture 2, so that

the entire pocket falls inside the bag. A flap 4 sewed, or otherwise secured to the bag 1 above the aperture 2, may be advantageously used and provided with an ordinary fastening mechanism such as a buckle 5. It will thus be seen that when golf balls or other articles are placed within the pocket, they are held entirely on the inside of the bag and there is no disfiguring bulge, or other irregular contour given to the outside of the bag, which presents a neat appearance.

Another form of pocket which I have found highly satisfactory, and which is of a slightly different type, is illustrated in Fig. 3. In this figure the caddy bag 1 is provided with an interior lining 6 of a material such as heavy cloth, canvas, leather, or the like. An aperture 7 of somewhat larger area than in the former example, provides access to the pocket.

In forming the pocket I provide lines of stitching passing through the wall of the bag 1 and the lining 6, and in this particular instance, the stitching takes the form of a rectangle, the short wall of which occupies a position just above the opening 7 and extends to near the bottom of the bag. This construction provides a much larger pocket than is the case in the other example shown, and this pocket may be used for larger articles, such as golfing shoes, refreshments, or other packages which the golfer may desire to carry with him. It will be perfectly apparent that articles in this pocket will be separate from the sticks carried in the bag. This type of pocket is also highly desirable because it requires no additional material within the bag, as the pocket proper consists, on one side of the bag lining, and on the other side, of the bag itself.

In order to properly protect such larger articles as might be spoiled by dampness and rain, I provide a flap 8 which is provided with a finger pull 9. Side flaps 10 and 11, sewed to the bag 1, are designed to overlap each other, one of the flaps, 10, having a metallic loop 12 secured thereto adapted to penetrate an aperture 13 in the flap 11. A strap 14 secured above the flaps 10 and 11 may now be made to pass between the flap

2
11 and the metallic loop 12, and be securely fastened, as by buckle 15. Additional means to protect the articles within the pocket from theft, is shown to consist of 5 the metallic rings 16 at the end of the strap 14 and a metallic ring 17 on the end of the strap holding buckle 15. Through these rings may be passed a padlock 18, which thereby prevents unauthorized access to the 10 pocket. A different arrangement of flaps may be utilized, as for instance, it may be desirable to first secure together flaps 10 and 11, and then overlay these parts with the flap 8, which, in this case, would be provided with an aperture 19 adapted to receive the metal loop 12 and the strap 14, as 15 before. Thus articles within the pocket

would be effectively protected from rain running down the side of the bag.

Having thus described my invention, what 20 I claim is:—

A golf bag comprising a substantially cylindrical member, an opening in the side of said member, closed by a flap cut from and integral with said member, the line of cutting defining said flap the uncut portion constituting a hinge, and a backing within the cylindrical member attached to said member and around said opening, whereby 25 an inner pocket is formed.

30 In testimony whereof, I affix my signature.

GEORGE L. PIERCE.
